KNEE CONTROL FOR ACCELERATORS

Emerson F. Taylor, Cincinnati, Ohio

Application October 13, 1938, Serial No. 234,857

2 Claims. (Cl. 74—515)

My invention relates to automotive vehicles and has among its objects and advantages the provision of an improved knee control for accelerators.

5 An object of my invention is to provide a knee control which may be operatively connected with the foot control of a conventional accelerator in which the knee control is so designed as to permit knee or foot actuation. The knee control is 10 shiftable to inoperative positions in addition to embodying adjustment to satisfy the needs of a particular driver.

In the accompanying drawing:

15 Figure 1 is a sectional view of a portion of an automobile illustrating the manner in which my invention is operatively connected with the foot actuated part of the accelerator;

20 Figure 2 is a front view taken from the position indicated by line 2—2 of Figure 1 with a portion of the instrument panel broken away for the sake of clearness;

Figure 3 is a view taken from the position indicated by line 3—3 of Figure 1;

25 Figure 4 is a sectional view along the line 4—4 of Figure 5;

Figure 5 is a sectional view along the line 5—5 of Figure 4;

Figure 6 is a perspective view of a portion of the device;

30 Figure 7 is an elevational view of the knee pad arm;

Figure 8 is a sectional view along the line 8—8 of Figure 7; and

35 Figure 9 is a perspective view of a different form of connection between the knee actuated means and the foot pedal.

In the embodiment selected to illustrate my invention, the usual foot board is illustrated at 10. The accelerator pedal 12 is pivotally mounted at 14 upon the foot board 10, and is connected with the accelerator rod 16 in the usual manner. Rod 16 is operatively connected with the throttle valve of the engine in the usual manner. Such throttle valves and operating connections are old and well known in the art and need not be described in further detail. Fire wall 18 is provided with an opening 20 for slidably receiving a shaft 22, which may be provided with a collar 24 45 to prevent complete withdrawal of the rod 22 from the opening 20.

To the instrument panel 26 I connect a bearing block 28, which includes a bore 30 for slidably supporting the shaft 22. Panel 26 includes a 55 right-angular flange 32 positioned in the slot 34

in the bearing block 28. Block 28 is fixedly related to the flange 32 by a set screw 36 threaded into the block. To one end of the shaft 22 I connect a head 38 provided with a slot 40 within which I mount one end of a knee bar 42. Head 38 includes a bore 44 for receiving the shaft 22, and the two parts are fixedly related by means of a pin 46. The curved end 48 of the knee bar 42 is pivotally connected with a shaft 50 carried by the head 38.

End 48 is provided with a series of notches 52 which may be brought into registration with a spring pressed latch ball 54 through rotation of the knee bar 42 about the axis of the shaft 50. Head 38 is bored for the reception of a compression spring 56 which urges the ball 54 into latching relation with the notches 52. Shaft 22 may be rotated by applying lateral pressure on the knee bar 42, while the latter may be latched in different positions to suit the needs of the driver by rotating the bar about the axis of the shaft 50.

On the shaft 22 I mount an arm 58 having an opening 60 in one end for slidably receiving the shaft. The shaft is provided with a plurality of recesses 62 for receiving the inner end of a set screw 64 threaded into the arm 58. Thus the arm 58 may be shifted longitudinally of the shaft 22 and fixedly related thereto through the medium of the set screw. The outer end of the arm 58 is bifurcated at 66 for accommodating a rod 68 having its lower end pivotally connected at 70 with the accelerator pedal 12. I provide the rod 68 with a plurality of transverse openings 72 for the reception of a cotter pin 74 passed through openings in the bifurcated end of the arm 58. Thus the rod 68 may be adjusted for operating length. To the knee side of the bar 42 I connect a sponge rubber pad 76, which pad is mounted on a plate 78 provided with pins 80 slidably in the slot 82 in the bar. A tension spring 84 has one end connected with one of the pins 80 and its other end anchored to a screw 84 threaded into the bar 42. Spring 84 holds the pad 76 in the normal position of Figure 8, but the pad may be shifted downwardly of the bar 42 against the tension of the spring 84. Pad 76 provides a cushion for the knee of the operator, while the slidable mounting for the pad permits the same to shift downwardly of the bar 42 as the shaft 22 is rotated for imparting a thrust to the rod 68. In other words, the pad 76 remains fixedly related to the knee of the operator so as to eliminate rubbing thereon.

Shaft 22, while rotatably related to the block 55

28, is keyed against relative longitudinal movement. The shaft is provided with a plurality of circumferential grooves 88 for the selective reception of a key pin 90 having a right-angular 5 end 92 arranged to rest on the top face of the block. Shaft 22 may be rotated freely, and the grooves 88 provide means for selective reception of the key pin 90 to the end that the shaft may be adjusted longitudinally to suit the needs of 10 the user. Block 28 is cut away at 93 to provide an abutment 94 arranged in the path of a stop pin 96 carried by the shaft 22. Stop pin 96 engages the abutment 94 when the accelerator 15 pedal 12 is in its normal position of Figure 1 to prevent further rotation of the shaft. However, the abutment 94 is so related to the stop pin 96 as to permit sufficient rotation of the shaft 22 for acceleration purposes. I provide the shaft 20 22 with a plurality of bores 98 for the selective reception of the stop pin 96 so that the latter may be shifted for engagement with the abutment 94 when the shaft 22 is adjusted longitudinally. The bores 98 are located midway between the circumferential grooves 88 so that the stop pin 96 may 25 be properly positioned when the shaft 22 is shifted and the key pin 90 is associated with a different groove.

The knee control is applicable to vehicles of 30 conventional design, and the control is so related to the foot operated accelerator as to permit foot operation in the usual way. At the same time, the accelerator may be operated entirely through 35 the medium of the knee control at the choice of the driver. Shaft 22 is adjustable longitudinally so as to accurately position the knee bar 42 at the most comfortable position for the driver. Similarly, the knee bar 42 may be pivotally adjusted 40 about the axis of the shaft 50 so as to give the user further adjustment for comfortable operation.

In Figure 9, I illustrate a different form of 45 connection between the shaft 100, which corresponds to the shaft 22, and the foot pedal 102. Foot board 104 is provided with the usual slot 50 106 for accommodating the accelerator rod 108. The flexible casing 110 of the flexible wire 112 extends through the slot 106 and is fixedly connected with a bracket 114 which may be secured to the wall 116 by a screw 118. One end of the 55 flexible wire 112 is fixedly connected at 120 with a bracket 124 secured to the foot pedal 102.

The opposite end of the flexible wire 112 extends through an opening in a projection 126 attached to an arm 128 corresponding to the arm 58. Projection 126 is provided with a set screw 130 arranged to have pressure relation with the wire 112 for making the wire secure to the projection.

Arm 128 is secured to the shaft 100 through the medium of a set screw 132 having its inner end arranged to be selectively positioned in recesses 134 in the same manner as the set screw 64. According to Figure 9, the arm 128 is positioned on the opposite side of the wall 116, which arrangement is permitted through the medium of the flexible wire 112 which may pass underneath the foot board 104 and up through the slot 106 for connection with the bracket 124.

Figure 1 illustrates the head 38 as being positioned adjacent the block 28. It will be noted that the pivotal axis for the knee bar 42 is located beneath the block 28 so that the knee bar may be swung upwardly underneath the instrument panel 26 so as to be hidden from view. Thus the operator may render the knee bar 42 inoperative and shifted to a position which gives the operator unobstructed knee room in the event that he should choose to employ the foot 20 control only. The lower point of the block 28 is curved so that the knee bar 42 may be rotated relatively thereto without interference when shifted to an inoperative position.

I claim:

1. In a knee controlled accelerator of the type described, including a rotatable rod, a support, a body fixed to said support and having a bore for slidably and rotatably supporting said rod, said rod being provided with a series of circumferential grooves, said body having a second bore, a pin slidable in said second bore and selectively receivable in said grooves for latching the rod against relative longitudinal movement in different positions thereof but permitting rotation of the rod, an abutment on said body, said rod being provided with a series of bores, and a stop pin selectively and frictionally receivable in the bores in said rod and arranged for engaging said abutment for limiting the relative movement of said rod, the bores in said rod being so spaced relatively to said grooves as to position the stop pin in the path of said abutment when the stop pin is positioned in a preselected bore and said first pin is inserted in a correspondingly preselected groove.

2. In a knee controlled accelerator device of the type described, a pivotal knee actuated member, a knee engaging pad, and means for slidably connecting the knee engaging pad with 50 said knee actuated member, said knee engaging pad sliding relatively to said knee actuated member when the latter is pivoted but remaining in the same position with respect to knee engagement.

EMERSON F. TAYLOR.
